UNITED STATES PATENT OFFICE.

LOUIS BRACCO, OF NEW YORK, N. Y.

MOLD-MACHINE FOR CONCRETE BUILDING-BLOCKS.

1,308,838.

Specification of Letters Patent. Patented July 8, 1919.

Application filed July 1, 1916. Serial No. 107,121.

To all whom it may concern:

Be it known that I, LOUIS BRACCO, a citizen of the United States, and a resident of the borough of the Bronx, Bronx county, 5 city and State of New York, have invented certain new and useful Improvements in Mold - Machines for Concrete Building-Blocks, of which the following is a specification.

10 My present invention is more or less particularly adapted for use in the production of concrete building blocks such as are illustrated and described in my pending application, Serial No. 97,647, filed May 15th, 1916
15 for concrete building blocks and has for its object the production of blocks molded in the form of two separated block sections having air spaces between them but united by means of stirrups or wire bails, the air
20 spaces being provided to prevent the transmission of moisture from one of the block sections to its companion block section and the stirrups or wire bails being provided to bridge such intervening air space.

25 To this end my invention comprises a novel arrangement of parts to be herein-after described.

In the accompanying drawings, Figure 1 represents a plan view of my construction; 30 Fig. 2 represents a side elevation thereof;

Fig. 3 represents a front elevation thereof;

Fig. 4 represents a section taken on line 4—4 of Fig. 2;

Fig. 5 represents a side-elevation, partly 35 in section with the mold box in tilted position;

Fig. 6 represents a detail in perspective of one of the end cores of the mold-box, and 40 Fig. 7 represents a sectional view similar to Fig. 4 showing a modified form of core.

Like reference numerals represent like parts in the several figures illustrating the embodiment of my invention.

In these drawings 10—10 represents a pair. 45 of beams which are intersected by cross-beams 11—11 to form a frame or stand whereon a mold-box 19 and associated parts are supported. This frame or stand also supports a turntable to be herein-after 50 described.

Mold-box 19 is mounted upon an angular frame formed of a pair of bars 34, (shown in Fig. 2 in a vertical position) said bars being cross-connected at their upper ends by a 55 cross-bar 35. At their lower ends these bars 34 are intersected by and secured to a pair

of bars 34^a (shown in Fig. 2 in horizontal position) said bars 34^a being cross-connected by a cross-bar 34^b.

The angular frame at the intersection of 60 the bars 34 and 34^a is hingedly connected as shown at 18 to a block 16^a secured on the turntable 13^a so that said frame and its mold-box 19 may be tilted at right angles from the position shown in Fig. 5 to the position shown in Fig. 2. Fig. 2 illustrates the mold-box when it is in position for removal of the cores and of the finished concrete block. The angular frame when in the position of Fig. 2 is supported by brackets 16^b, 65 70 while when in the position of Fig. 5 it is supported by the horizontal bar 16.

The mold - box 19 comprises three side walls 20, 20^a and 20^b, each of said side walls being hingedly secured, as shown at 34^a, to 75 the parallel bars 34^a of the angular frame, so that they may be swung from vertical position (which is the normal position while the box 19 is being filled) downwardly to a position to permit of the removal of the finished cement block. A hinged top plate 21 and a base plate or pallet 22 are provided and comprise with the side walls 20, 20^a and 20^b, the five inclosing panels for the mold-box 19, leaving the opening 19^a through 80 85 which the concrete is introduced in forming the block. The top plate 21 has openings 27 and 28 to permit of the insertion and removal of the cores 29 and 30 hereinafter described. It is provided also with latches 21^a 90 which engage with keepers 21^b secured at the forward upper ends of the side walls 20^a and 20^b.

The two side walls 20^a and 20^b are each 95 formed with inwardly projecting cores 23 and with smaller cores 24, the latter of which being made removable from the cores 23, if desired, and being provided with recesses 25 for maintaining in position during the molding of the block a wire stirrup or 100 tie 26, which tie, becoming embedded in the concrete during the molding of the block sections 26^a and 26^b serves firmly and permanently to unite the two separated block sections 26^a and 26^b of my concrete block 105 construction. A central removable core 29 and two adjacent smaller removable cores 30—30, one at either side of the central core 29 and projecting into abutment with the cores 24, comprise the center cores for my 110 block box and provide for the separating air space between the block sections, thus keep-

ing them from contact with one another, as best shown in Fig. 4 of my drawings.

The turntable which supports the mold-box when being filled comprises a stationary platform 13 and a superimposed platform 15, the latter being revoluble relative to the platform 13 by means of a ball race 14. The two platforms are held in proper relative position by means of a pin or pivot 17 passing centrally through both platforms. By revolving the platform 15, the mold-box may be brought into any desired position relative to the operator.

Fig. 5 represents the mold-box after the bottom of the mold-box has been covered with concrete and after the cores 29, 30, 23 and 24 as well as the stirrup or bail wires 26 have been placed in position as shown in said figure. Additional concrete (which may be in a more or less plastic state) is thereupon supplied to the box and jammed into it by means of a tamper until it is filled flush up to the open side 19^a of the mold-box. The block will thus be formed in the desired shape as determined by the cores and the wire will have become embedded in the cement of the oppositely located block sections 26^a and 26^b, and, bridging the space between them will firmly bind these sections together. To remove the cement block sections the box 19 is tilted to the position of Fig. 2, the cores 29 and 30 are removed, the side walls 20, 20^a, 20^b and the cover 21 are thrown open on their hinges and the pallet 22 upon which the cement block is now supported is lifted out.

In Fig. 7 I have shown my mold-box with the side cores 23 and 24 removed from one of the side walls, this mold being intended for the formation of corner blocks. In this view I have shown a core 37 swung on a rod 38 by means of eyelets 39 in core 37. This core 37 comprises three parts, the main part 40, the angular hinged extension 41, and the hinged stay plate 42 which holds the angular extension 41 in its operative position. In addition to the cores 23-24 a filler core 43 may be inserted to give the block the shape shown.

50 When the corner block, for which this con-

struction of cores is designed, is completed the stay plate 42 is swung upwardly to give slight play to the angular extension 41 so that the core 37 may be withdrawn without undue binding in the concrete.

55 I have shown more particularly in Fig. 3 of the drawings perforations in the cross-bars 35 and 34^b which may be provided for the purpose of enabling the mold-box to be extended in its lengthwise direction. Obviously when the mold-box is so extended a pallet 22 and a cover 21 of appropriate length would have to be substituted to make up for such elongation. If my mold-box should be adjusted to certain fixed dimensions for the block sections and it be desired to reduce such dimensions, it will be necessary only to insert extra cores or blocks in the mold as adjusted, whereby, naturally, a block of reduced dimensions would be 70 molded.

75 While I have shown my invention in one specific form of construction, it will be understood that the same may be practised in numerous other forms and in connection with a variety of dimensions as to both the block box proper and the cores and the metallic tie shown in my drawings, without departing from the spirit of the invention. This is true also of numerous details of construction which may be varied at will without 80 avoiding the essence of my device.

85 What I claim is:

A mold box for forming concrete building blocks provided with a removable center core, removable cores of reduced width at opposite sides of said center core, a pair of hinged side walls for said box, an inwardly extending core secured upon each of said walls, an additional inwardly extending removable core of reduced width carried by each of said last named cores, said cores being adapted to form a block in two separate sections having projections extending toward each other, and a metallic tie supported between said pairs of cores of reduced width to engage said projections and connect said separate sections.

90 95 LOUIS BRACCO.
